UNITED STATES PATENT OFFICE

ROY DOUGLAS, OF MEXIA, TEXAS, ASSIGNOR OF ONE-FOURTH TO ASSOCIATED FACTORIES CORPORATION, OF DALLAS, TEXAS, A CORPORATION OF DELAWARE

WORKING-BARREL HONING DEVICE

Application filed June 30, 1928. Serial No. 289,553.

My invention relates to a working barrel honing device and has particular reference to an apparatus for honing, milling, reaming or boring out the liners within the working 5 barrel section of a well casing without the necessity of removing said liners from the jacket in which they are secured.

The working barrel of ordinary oil well equipment is generally positioned at the bottom 10 of the well and is carried at the lower end of the well casing, and usually consists of a jacket containing ten or more tubular metal liners which are placed end to end within a jacket to constitute the working 15 barrel or cylinder within which the pump plunger is reciprocated to force the oil from the bottom of the well to the surface. After prolonged usage, these liners become worn and scored and thus render the operation of 20 the pumping equipment unsatisfactory, and when this condition arises, it is necessary to remove the working barrel from the well and to repair or replace the liners in order to insure a proper and effective fit between 25 the pump plunger and the liners. Heretofore it has been the practice to completely remove the individual liners from the jacket after the working barrel has been "pulled" or brought to the surface, and to replace 30 them with new ones, each of the individual liners, usually ten or twelve in number, being subsequently ground down or honed to correspond to the diameter of the pump plunger piston, or it has been the practice 35 to remove the individual liners from the jacket and to grind or hone each liner to remove the score marks and pit holes and to further grind or hone them to properly accommodate an "oversize" pump plunger piston. 40 No apparatus has heretofore been available by means of which the working barrel liners could be ground or honed to the proper size and shape without the necessity of completely removing each individual liner 45 from the jacket and subjecting it to the described operation of grinding or honing.

It is the object of my invention to provide a device or apparatus whereby the tubular liner within the ordinary working barrel can be ground, honed, bored, or other-

wise worked upon without the necessity of removing the liners from the jacket in which they are secured.

It is a further object of my invention to provide an apparatus for operating on the 55 liners of an ordinary working barrel without necessitating the removal of said liners from their jackets, said apparatus including a novel work holder for supporting and maintaining the complete working barrel 60 in exact vertical alinement, and to associate with said work holder novel means for rotating and reciprocating within the liners, a hone or other tool to effect the proper resurfacing or resizing of the complete set of 65 liners within their jacket.

It is a still further object of my invention to provide a complete working barrel honing device which is simple in construction, 70 cheap and easy to manufacture, reliable in operation, and highly efficient in the purposes for which designed.

In the accompanying drawings forming a part of this specification and in which like numerals are employed to designate like 75 parts throughout the several views,

Fig. 1 is a side elevation, partly in section, showing my complete apparatus in position to operate upon a jacket placed within the stationary work holder;

Fig. 2 is an enlarged vertical sectional view showing the details of the work holder and the rotary, reciprocating honing device associated therewith;

Fig. 3 is an enlarged perspective view of 85 the set of wedge-shaped slips which are used to hold the jacket in alinement within the stationary work holder;

Fig. 4 is a perspective view of my complete apparatus;

Fig. 5 is an enlarged sectional view on the line 5—5 of Fig. 2;

Fig. 6 is an enlarged sectional view on the line 6—6 of Fig. 2, and

Fig. 7 is a fragmental, perspective view of 95 the connection between the drive shaft and the hone.

Referring to the drawings, wherein for the purpose of illustration is shown a preferred embodiment of my invention, the nu- 100

meral 1 designates broadly my improved stationary work holder, the same comprising a tubular casing 2 of a length and diameter sufficient to accommodate the ordinary or standard working barrel. The tubular casing 2 is buried in the ground below the floor 3 of the work shop and is preferably embedded in cement 4, which assists in maintaining the said casing in exact vertical alignment. The upper open end of the casing 2 extends upwardly through the floor 3 of the work shop, and the lower end of said casing is provided with a nipple 5 having inwardly and downwardly tapered inner walls, this nipple being screw threaded onto or otherwise secured to the casing. The numerals 6 and 7 represent a pair of coacting slips, each having their outer surfaces tapered and having their inner surfaces provided with grooves 8 or teeth, the grooves or teeth 8 of slip section 6 being arranged axially of the section, whereas the grooves 9 of the slip section 7 are arranged transversely of the section, for purposes to be hereinafter described.

Referring to the operation of my improved work holder 1, constructed and mounted as above described, the jacket 10 of the working barrel of an oil well pumping equipment is placed above the work holder 1 and lowered thereto, it being understood that the jacket 10 contains the liners 11 which constitute the working cylinder of the pumping mechanism of the well. Preferably the jacket 10 is provided at its upper and lower ends with an internally screw threaded collar 12, it being noted that the internal threads on opposite ends of each collar 12 are of different diameters, to thereby accommodate casings and well tubings of different diameters. The collar 12 at the lower end of the jacket 10 contacts with the downwardly and inwardly sloping walls of the nipple 5 and thus the jacket 10 is centered within the work holder 1 with the upper end of the said jacket projecting above the upper open end of the work holder as clearly shown in Figs. 1 and 4 of the accompanying drawings. The coacting slips 6 and 7 are now placed around the upper projecting end of the jacket 10 and are hammered down into the upper open end of the tubular casing 2, the tapered outer surfaces of said slips contacting with the said tubular casing and, by a wedging action, causing the axial teeth 8 and the circumferential teeth 9 to bite into the jacket 10 to thus maintain the jacket rigidly within the casing and to prevent rotary or vertical movement of the jacket with respect to the said casing. The jacket 10 and its contained set of liners 11 is now in position for the grinding or honing operation.

The grinding or honing section of my improved apparatus includes a tool adapted to be rotated and reciprocated within the set of liners positioned within the stationary work

holder as above described, and further includes a pair of vertical guides or standards 13 arranged on opposite sides of the stationary work holder 1 and secured to the floor 3 and ceiling 14 of the workshop, said guides or standards 13 being parallel to each other and each parallel to the vertical axis through the stationary work holder 1, these standards 13 constituting guides to control the vertical movements of the vertically-reciprocating rotary tool which is used for the grinding or honing operation. An electric motor 15 is suspended from the ceiling 14 by means of a flexible cable 16 which passes over sheaves or pulleys 17 secured to the ceiling 14, this cable being provided at its free end with a counter-weight 18 of sufficient size or weight to balance the motor and the parts carried thereby. The casing of the motor 15 has formed integrally therewith or appropriately secured thereto a pair of laterally extending arms 19 which constitute handles and which are of a sufficient length to engage on opposite sides of the vertical guides or standards 13 and by means of which the motor may be moved up and down by the operator of the apparatus. It is, of course, understood that the motor 15 is so positioned between the vertically extending guide standards 13 as to be suspended directly above the stationary work holder 1.

The motor 15 is provided with a relatively long depending drive shaft 20 which terminates in a ball-shaped end portion 21 by means of which the said drive shaft is flexibly connected to a socket 22 on the hone or other tool which is to be driven within the set of liners rigidly held within the stationary work holder. In the drawings accompanying my application, I have shown a hone or grinding tool comprising a body portion 23 and radially movable segmental abrading or grinding members 24, these grinding members 24 being radially movable by means of upper and lower wedges 25 which are moved relative to each other by means of the adjusting sleeve 26 mounted on the screw threaded centrally-located rod 27. This form of expandible and contractable hone or grinding device is old and well known in the art and forms, of itself, no part of my present invention.

At the upper end of the drive shaft 20 at a point relatively close to the motor 15, I secure a collar 28, while at the lower end of said drive shaft 20 at a point relatively close to the ball-shaped portion 21, I secure similar collar 29, these two collars 28 and 29 being keyed or otherwise secured to the shaft so as to rotate therewith. Positioned around the drive shaft 20 and extending between the two collars 28 and 29, I provide a tubular outer casing 30 having secured at its upper end a collar 31 and at its lower end a collar 32, the end faces of these two collars 31 and 32 being

flattened off or otherwise shaped to constitute one member of an antifriction thrust bearing. The ends of these two collars 31 and 32 are relatively close to the two collars 28 and 29 respectively and between these respective sets of collars, I place a ball, cylinder, or other type of end or thrust bearing, by means of which the shaft may be rotated within the stationary outer casing 30 with the minimum friction between the end bearings. I also preferably place a bronze or other type of bearing 33 within the stationary tubular casing 30 and surrounding the inner rotating shaft 20 so as to maintain the shaft 20 in exact alignment within the said stationary casing. Near the upper end of the stationary casing 30, preferably immediately adjacent the upper collar 31, I provide a transversely extending guide bar 34 having forked end portions which engage on opposite sides of the vertical guides or standards 13 to thus insure that the motor, shaft and associated parts partake of a true vertical movement during the reciprocating movements of the device. The 25 guide bar 34 has a tight fit with, or is otherwise rigidly secured to, the tubular outer casing 30 so as to hold the same against rotation.

Referring to the operation of my improved device as a whole, the working barrel jacket 10 after having been removed from the well and disconnected from the string of well casing, is positioned within the stationary work holder 1 and rigidly secured thereon, as described in detail in the preceding paragraph of this specification. The ball-shaped head 21 is inserted in the socket 22 of the hone or grinding device and is secured thereto by the transverse locking pin 35 which 40 is adapted to transmit the drive from the motor 15, through the shaft 20 to the hone or grinding device. The adjusting screw 26 is operated to draw the wedges 25 together to thus move the grinding strips 24 radially 45 to the proper diameter to grind the liners 11 within the jacket 10 as required. The hone or grinding device is then inserted through the collar 12 at the upper end of the jacket 10 and is moved downwardly into the interior 50 of the tubular liners 11 within the casing. The motor 15 is then started to impart rotation to the hone or grinding device and the operator by means of the handles 19, reciprocates the motor and its associated parts vertically so as to move the hone or grinding device throughout the entire axial length of the working barrel jacket to effectively grind the entire set of liners 11 contained therein. During this operation, the jacket 10 and its 55 associated liners 11 are retained against rotation and against vertical displacement within the stationary work holder 1 by means of the coating slips 6 and 7. The reciprocatory movements of the motor 15 and its associated parts are constrained to true vertical move-

ment because of the sliding engagement between the guide bar 34 and the vertical, alined guides or standards 13. The vertical movement of the motor 15 is transmitted to the hone or grinding device through the drive shaft 20 and outer stationary casing 30, this stationary casing 30 keeping the shaft 20 in exact vertical alinement and preventing any bending or flexure of the said shaft during the grinding or honing operation. The 70 grinding or honing operation proceeds until the hone is no longer effective to act on the liners, that is, until the internal diameters of the said liners have been reduced to the diameter of the hone in its adjusted position, at which time the motor is stopped and the motor and its associated parts are moved to the uppermost position, the adjusting screw 26 is manipulated to increase the effective diameter of the hone, and the hone is again inserted 75 within the liners and the operation proceeded with as aforesaid, until such time as the scorings or pit holes have been removed from the inner surface of the liners or the liners have been increased to the proper and predetermined internal diameter to accommodate an 80 "oversize" pump piston.

It will thus be seen that I have provided a device or apparatus, by means of which the liners within the working barrel of an oil well pumping equipment can be readily honed or ground while in position within their jacket and without the necessity of removing the said liners from the said jacket. While I have shown and described my apparatus as used for grinding or honing, it is quite obvious, and entirely within the scope of my invention, to substitute for the hone shown and described, some other type of tool by means of which the liners may be milled, reamed, bored or otherwise acted upon. It is to be understood that the form of my invention herein shown and described is to be taken as a preferred example of the same, and that various changes in the shape, size and arrangement of parts may be resorted to without departing from the spirit of my invention or scope of the subjoined claims.

Having thus described my invention, what I claim is:

1. A working barrel honing device comprising a stationary work holder, means at the lower end of said work holder for centering the working barrel and its associated liners within the work holder, means at the upper end of said work holder for centering the working barrel and its associated liners within the work holder and for maintaining the working barrel against rotary or vertical movements therein, a rotary reciprocating tool suspended above the work holder and in vertical alinement therewith and adapted to operate on said liners to grind or hone the same to a predetermined internal 120 diameter.

diameter, a vertical guide standard positioned above the stationary work holder, and a guide bar associated with the tool and engaging the standard for guiding the said tool during its reciprocating movements.

5. 2. A working barrel honing device comprising a relatively long, vertically extending tubular casing adapted to accommodate the working barrel and its associated liners therein, means for maintaining the working barrel in vertical alinement within the casing for maintaining the same against rotary and vertical movements therein, a motor suspended above the work holder and having a long depending shaft, said motor being capable of vertical movement, a rotary tool attached to the lower end of the shaft and driven thereby and adapted to operate on said liners to grind or hone the same to a predetermined internal diameter, and means for guiding the shaft during its reciprocating movements.

3. A working barrel honing device comprising a vertically extending tubular work holder adapted to accommodate therein the working barrel and its associated liners, means within said work holder to center the working barrel and to prevent rotary or reciprocating movements of the said barrel within said work holder, a motor suspended above the work holder and having a long depending shaft, said motor being capable of vertical movement, a rotary tool attached to the lower end of the shaft and driven thereby and adapted to operate on said liners to grind or hone the same to a predetermined internal diameter, a casing surrounding the depending drive shaft and extending between the tool and motor, a vertical guide standard positioned above the stationary work holder, and a guide bar secured to the casing and engaging the standard for preventing rotation of the casing and for guiding the drive shaft and its associated parts during vertical movements thereof.

4. A working barrel honing device comprising a tubular work holder mounted in vertical position and adapted to accommodate therein the working barrel and its associated liners, a pair of tapered segmental slips inserted in the upper end of the work holder between the sides thereof and the working barrel for centering the said barrel and for preventing rotary or reciprocating movements of the said barrel within said work holder, a rotary reciprocating tool supported above the work holder and adapted to operate on said liners to grind or hone the same to a predetermined internal diameter, and means for guiding said tool during its reciprocating movements.

5. A working barrel honing device comprising a tubular work holder mounted in vertical position and adapted to accommo-

date therein the working barrel and its associated liners, a pair of tapered segmental slips inserted in the upper end of the work holder between the sides thereof and the working barrel for centering the said barrel, one of the segmental slips having its inner surface provided with axially extending teeth which bite into the outer surface of the working barrel to prevent rotary movement of the said barrel and the other of said slips having its inner surface provided with circumferentially extending teeth which bite into the outer surface of the working barrel to prevent vertical movement of the said barrel, a rotary reciprocating tool supported above the work holder and adapted to operate on said liners to grind or hone the same to a predetermined internal diameter, and means for guiding said tool during its reciprocating movements.

6. A working barrel honing device comprising a work holder including a tubular casing adapted to accommodate therein the working barrel and its associated liners, a nipple at the lower end of said casing having inwardly and downwardly tapered inner walls with which the lower end of the working barrel contacts to automatically center the said barrel within the casing, means at the upper end of said work holder for centering the working barrel and preventing rotary or vertical movements thereof, and a tool reciprocable within the working barrel to grind or hone the liners within said barrel to a predetermined diameter.

7. A working barrel honing device comprising a work holder including a tubular casing adapted to accommodate therein the working barrel and its associated liners, a nipple at the lower end of said casing having inwardly and downwardly tapered inner walls with which the lower end of the working barrel contacts to automatically center the said barrel within the casing, tapered segmental slips inserted in the upper end of the work holder between the inner sides thereof and the working barrel for centering said barrel and for preventing rotary or vertical movements of the barrel within the work holder, and a tool reciprocable within the working barrel to grind or hone the liners therein to a predetermined diameter.

8. A work holder for the working barrels of well casings, comprising a relatively long tubular casing adapted to accommodate therein the working barrel and its associated liners, a nipple at the lower end of said casing having inwardly and downwardly tapered inner walls with which the lower end of the working barrel contacts to automatically center said barrel within the casing, and a pair of tapered segmental slips inserted in the upper end of the work holder between the sides thereof and the working barrel for centering said barrel, one of said

segmental slips having its inner surface provided with axially extending teeth which bite into the outer surface of the working barrel to prevent rotary movement of said barrel and the other of said slips having its inner surface provided with circumferentially extending teeth which bite into the outer surface of the working barrel to prevent vertical movement of the said barrel, and a tool reciprocable within the working barrel to grind or hone the liners therein to a predetermined diameter.

In testimony whereof I hereunto affix my signature.

ROY DOUGLAS.
